(57) **CLAIM**

The ornamental design for a food container, as shown and described.

DESCRIPTION

FIG. 1 is a front view of a first embodiment of a food container showing our design, wherein the rear view, the side views, the top view and the bottom view thereof have no ornamental features; and,

FIG. 2 is a front view of a second embodiment of a food container showing our design, wherein the rear view, the side views, the top view and the bottom view thereof have no ornamental features.

The broken lines shown herein are for illustrative purposes only and form no part of the claimed design.

The stippling shown herein indicates securing of a first side of the food container to a second side of the food container.
